Filed Jan. 6, 1972, Ser. No. 215,985

Term of patent 3½ years

Int. Cl. D11—04
U.S. Cl. D29—1 A

Fig -1

Fig -2

FIG. 1 is a front elevational view of an artificial Christmas tree showing my new device. The rear and side views of the tree are the same as in FIG. 1 since all four sides of the tree are the same; and

FIG. 2 is a top plan view.

I claim:

The ornamental design for an artificial Christmas tree, substantially as shown and described.
